By myself, James Warren
Attest,

UNITED STATES PATENT OFFICE.

WARREN B. WHITE, OF NORTH ABINGTON, MASSACHUSETTS.

WELT FOR BOOTS AND SHOES.

997,350.

Specification of Letters Patent. Patented July 11, 1911.

Application filed December 17, 1910. Serial No. 597,747

To all whom it may concern:

Be it known that I, WARREN B. WHITE, a citizen of the United States, and a resident of North Abington, in the county of Plymouth and State of Massachusetts, have invented an Improvement in Welts for Boots and Shoes, of which the following description, in connection with the accompanying drawing, is a specification, like reference characters on the drawing representing like parts.

This invention relates to welts for boots and shoes as an article of manufacture.

The character of the invention may be best understood by reference to the following description of illustrative embodiments thereof shown in the accompanying drawing, wherein:

Figure 1 is a section through a shoe having a welt embodying the invention; Fig. 2 on an enlarged scale is a sectional detail of parts shown in Fig. 1; Fig. 3 is a view similar to Fig. 2 showing a slightly modified form of welt; Fig. 4 is a sectional view illustrating a step in the manufacture of the welt shown in Fig. 1; Fig. 5 is a sectional view of the welt shown in Fig. 4 complete. Fig. 6 is a plan view of Fig. 5; Fig. 7 is a sectional view illustrating a step in the manufacture of a modified form of welt; and Fig. 8 is a sectional view showing the latter welt complete.

Referring to the drawing, in Fig. 1 is shown a shoe comprising the usual upper 1, insole 3 and a welt 5 embodying the invention. The welt has a longitudinal groove 6 on the under side thereof and is bent over and secured to the upper and inner sole by stitches 7 in the usual manner. An important feature of the invention consists in forming a flange 9 from the body of the welt. Herein said flange is formed by incising said welt as at one edge thereof, said flange being then bent to project upwardly from the upper face of the body of the welt. This flange may be variously formed according to the use to which it is to be put. In Figs. 1, 2, 3 and 5 it is doubled over on itself forming a bead or bight so that when applied to the shoe (Figs. 1, 2 and 3) its free edge is folded in against the upper adjacent the seam formed at the union of the upper with the insole. The spring of the leather tending to return the flange to the body of the welt from which it was bent may be sufficient to maintain said flange

against the upper, or said flange may be secured to the upper by stitching or by an adhesive as desired.

If desired the flange may be bent over and flattened somewhat and formed as shown in Fig. 3 to lie well under the upper to simulate the appearance of a shoe having a cork sole.

In some instances the flange need not be doubled on itself but may be of a single thickness as shown in Figs. 7 and 8. The flange may then have its free edge skived or otherwise finished to blend gradually to the upper against which it lies.

A welt such as described may be applied to Goodyear, McKay and other shoes and is found to present a very advantageous construction, adding to the attractive appearance of the shoe and its general strength and at the same time constituting a sort of dam for preventing ingress of water to said seam. Furthermore, the welt is simple in construction and cheap to manufacture.

Having described selected embodiments of the invention without limiting myself thereto, what I claim as new and desire to secure by Letters Patent is:

Claims.

1. An article of manufacture, a welt having a flange incised from the body portion thereof and bent therefrom to cover the seam at the junction of an upper with an insole.

2. As an article of manufacture, a welt having its body incised longitudinally thereof forming a flange, said flange being bent from said body to present a seam protecting member.

3. As an article of manufacture, a welt having its body incised longitudinally thereof forming a flange, said flange being bent from said body and doubled over to present a seam finishing bead.

4. As an article of manufacture, a welt having its body incised longitudinally thereof forming a flange, said flange being bent from said body to present a seam finishing member projecting outwardly from the upper face of the welt intermediate the longitudinal edges thereof.

5. As an article of manufacture, a welt comprising a body and a longitudinal flange incised from said body and bent to project therefrom intermediate the longitudinal edges thereof to form a water resisting dam at the union of the upper with the sole.

6. As an article of manufacture, a welt having a body provided with a portion adapted to be stitched to the upper; and a finishing bead incised and bent from said body adjacent said stitch receiving portion, said bead being formed to lie adjacent the union of the upper with the sole.

7. As an article of manufacture, a welt comprising a body having its edge slit longitudinally of the welt to form a portion adapted to be bent and stitched to an insole

and a finishing flange projecting from said body to lie adjacent the union of the upper with the sole.

In testimony whereof, I have signed my name to this specification, in the presence of two subscribing witnesses.

WARREN B. WHITE.
